INTERNAL COMBUSTION ENGINE
CONTROL

Martin J. Finnegan, New York, N. Y., and Howard Baer, Jersey City, N. J., assignors to Eclipse Aviation Corporation, East Orange, N. J., a corporation of New Jersey

Application January 9, 1936, Serial No. 58,324

5 Claims. (Cl. 188—1)

This invention relates to internal combustion engines and more particularly to means for controlling the rotation of the propeller shaft or other loads normally driven thereby.

5 While the invention is of decided utility when applied to engines used on airplanes, in which application it functions to bring the propeller to a full stop promptly upon cooling of the engine (following de-energization thereof) to a predetermined temperature, it is to be understood that in its broader aspects the invention is applicable to any internal combustion engine adapted to drive a load which has the objectionable tendency to continue in motion after de-energization of the engine.

10 If an airplane engine stalls for any reason, it is desirable to bring both the engine and its propeller to a dead stop in order to decrease the propeller drag and prevent any aggravation of the injurious effects which such failure of the engine produces. It is particularly necessary that this free rotation of the propeller be prevented in any installation where the propeller is located off the center line of the plane, as for example, in 15 a multi-engine plane. It is accordingly an object of the present invention to prevent such continued rotation of the propeller of an airplane engine which has for any reason failed.

20 In this respect the invention is an improvement upon that of Romeo M. Nardone, as disclosed in his Patent No. 1,967,966 of July 24, 1934, the improvements including:

25 First, the extension of the concept to include a plurality of such rotation arresting devices, to be actuated by means energized from a common source;

30 Secondly, the provision of novel heat responsive means for controlling such energization;

35 Thirdly, the provision of selective energizing means; and

40 Fourth, the provision of electromagnetic actuation for each rotation arresting device.

In the drawings,
45 Fig. 1 is a schematic representation of the parts involved in one embodiment of the invention when applied to two engines;

Fig. 2 shows the invention applied to three engines;

50 Fig. 3 is a diagrammatic view of a second embodiment, as applied to two engines; and

55 Fig. 4 shows this second embodiment applied to three engines.

Referring first to Fig. 1, reference character 5 designates one arm of a bellcrank having at its outer end a formation 6 adapted to receive a link

or other operating connection leading to the friction brake 8 operating, when drawn tight, to arrest the rotation of the propeller driving shaft 7, the said rotation arresting device corresponding in function to the friction brake operating connections shown at 99, 100, 102 and at 97 of Fig. 1 of the above identified Nardone patent, and constituting the means for arresting rotation of the engine driven propeller shaft 29 of said patent. A similar bellcrank arm 5' and formation 6' is shown for operation of a duplicate mechanism 8' for arresting the motion of a propeller shaft 7' of a second internal combustion engine (such as would be employed on a multi-engine aircraft). Each of the bellcranks 15 has its opposite arm adapted to be actuated in one direction by springs 31 and 32, and in the opposite direction by a plunger or core of an electromagnetic device, that for the bellcrank 5 being indicated at 10 and that for the bellcrank 5' at 11, and both being adapted to be energized from a common source 13 through parallel connections 14 and 15 and a plurality of switches A, B, C, D, adapted for selective actuation in accordance with the thermal conditions 20 in or adjacent the corresponding internal combustion engines (not shown).

25 Reference characters T₁ and T₂ designate the two separately acting elements of a heat responsive unit or thermostat adapted to actuate the switch contacts A and B respectively, to open or close said contacts in such manner that position of said contacts will correspond to that indicated in the drawings when the associated engine 30 is not running, the contacts moving to new positions when the engine has been running for a sufficient interval to generate the necessary heat increment to cause such movement. Switches C, D, respond similarly to the thermal conditions 35 of engine No. 2 by reason of the provision of the thermostat devices T₃ and T₄ having an action similar to that just described for the thermostat devices T₁ and T₂.

40 Preferably, thermostat T₁ is of the quickly responding type whereas thermostat T₂ is a 45 more slowly responding type so that very soon after the starting of engine No. 1, thermostat T₁ will operate to open the switch A while the closing of switch B by the heat absorbed in thermostat T₂ will take a longer interval, say several 50 minutes. Likewise, there is a differential action on the part of thermostats T₃ and T₄ the latter being of the quickly acting type and the former of the more slowly acting type whereby switch D will open almost immediately upon the starting 55

of engine No. 2 while the closing of switch C will be delayed several minutes. These thermostats may be of the type shown in Patent No. 1,994,807 granted to Kenneth R. Blake et al., March 19, 1935, and each of different wall thickness in order to obtain the differential action above referred to

From the foregoing it will be apparent that under the assumption that the invention is applied to an aircraft having two engines, to one of which the rotation arresting device 5 is applied, and to the other of which the rotation arresting device 5' is applied, the starting of the engines 1 and 2 will develop the necessary heat rise in devices T₁ and T₄ to cause movement of the switches A and D to the open position simultaneously, or in rapid sequence—it being assumed that both engines will be started substantially simultaneously. Several minutes later, when switches B and C move to the closed position, the solenoids 10 and 11 will remain de-energized, since the circuit to solenoid 10 is now open at switch A, and the circuit to solenoid 11 is now open at switch D. In other words, the closure of switches B and C has no effect, for the circuits thereto are open at the points A and D, respectively, as noted. This condition prevails during normal flight, that is, unless and until an engine "stalls".

However, should there be a subsequent stalling of engine No. 1, for example, the resulting return movement of the switch A to the closed position, as a result of the cooling of the said engine, will complete the circuit to the solenoid 10, the return line being by way of conductor 36, switch A, conductor 37, switch C, and conductor 38, this energization of the solenoid 10 producing a counterclockwise shifting of the bellcrank 5 and hence an application of the brake to the said engine No. 1.

Now if engine No. 2 should thereafter fail, so that both engines are dead, the resultant opening of switch C will break the circuit just traced to solenoid 10, and solenoid 11 also will remain de-energized, due to the open condition of switch B of the latter circuit. However, should engine No. 2 be the first to fail, rather than engine No. 1, the resultant closure of switch D, coupled with the fact that switch B is also closed (due to the heated condition of engine No. 1 and T₂), completes the circuit to solenoid 11 to apply the brake to engine No. 2 by way of conductor 15, solenoid 11, switches D and B, conductor 22, conductor 23 to battery 13.

The result is to cause application of the engine rotation arresting means automatically when one, but not both, engines have failed, while permitting the automatic release of the brake when both engines have failed, and also to prevent application of either brake prior to any actual failure of one engine.

When the embodiment of Fig. 1 is applied to three engines the arrangement is preferably as shown in Fig. 2 wherein there is an additional thermostatically controlled set of switches E and F adapted to be actuated by slow acting and quick acting thermostats T₅ and T₆ respectively, the switch F being in circuit with the solenoid 12 which applies the brake to engine No. 3 through mechanism corresponding to that of engines No. 1 and No. 2 previously described; and the switch E is in one branch of the circuit to the solenoid 10 as well as being also in circuit under certain conditions with the solenoid 11. Likewise the quick acting switches A and D are in circuit with the solenoids 10 and 11 respectively, of their as-

sociated engines, while the slow acting switches B and C are adapted for control of the circuits to the solenoids of the other engines—engines No. 2 and No. 3 in the case of switch B and engines No. 1 and No. 3 in the case of switch C. By reason of this arrangement of the switches and controlling circuits, all solenoids will remain de-energized during normal flight with all three engines in the running condition and therefore generating sufficient heat to hold switches F, A 10 and D open, but if any one of the three engines should fail the resulting closure of one of the three switches just referred to will close the circuit to the corresponding solenoid 10, 11 or 12 to apply the brake to the said engine and thereby 15 arrest its rotation. Thus, for example, if engine No. 3 should fail during flight the solenoid 12 would become energized by reason of the fact that the switches are in the following positions during normal flight:—

Switches A, D and F are open
Switches B, C and E are closed

but the cooling-off of thermostat T₆ due to the stalling of engine No. 3 would cause switch F to 25 close and thus complete a circuit to the solenoid 12 which is traceable from the battery 13 through conductors 31, 32, switch B, conductor 34, the now closed switch F and conductor 35 to the solenoid 12, the return circuit being by the way of 30 conductors 36, 37 and 38. Thus, the brake is applied to engine No. 3, but not to either of the other two engines (which, under the assumed conditions, will still be in operation), since the circuit to solenoid 10 is still open at the switch 35 A while the circuit to the solenoid 11 is still open at the switch D.

In choosing the time interval for the slow acting thermostats T₅, T₂ and T₃ it is suggested that the interval be great enough to embrace the 40 normal interval elapsing between the starting of the first and the starting of the last of the engines to be started. In the case of a three-motor plane this interval may extend over a period of several minutes; hence the foregoing suggestion that the 45 slow acting thermostat be set to act not sooner than several minutes after the first turning-over of the engine. If so set there is an assurance that the three engines will be started before any one of the three slow acting switches E, B or C moves to the closed circuit position. Thus, there is an assurance that none of the solenoids will be 50 prematurely energized.

In the modification of the invention shown, in Figs. 3 and 4 each set of switches AB, CD and EF 55 (the latter being employed only when there is a third engine as in Fig. 4) is actuated by a single thermostatic device so that the opening of the switch A for example, is simultaneous with the closing of the switch B and likewise with respect 60 to switches C and D for engine No. 2 and switches E and F for engine No. 3. The result is the same however, as in Figs. 1 and 2, that is, the starting of the engines causes a movement of the switches A, C and E to the open position thereby preventing energization of any one of the solenoids 10', 11' or 12', notwithstanding the simultaneous closure of the switches B, D and F, since each solenoid is in a circuit with at least one of the normally open switches. However, in the event 65 of a subsequent failure of one engine the resulting closure of its normally open switch will complete a circuit to its solenoid by way of said now closed switch and the normally closed switch of the related engine. Thus, for example, failure of 70

engine No. 1 in the two-motor arrangement of Fig. 3 will cause an energization of solenoid 10', the current flowing from source 13' by way of conductors 51 and 52 to the switch A and from said point by way of conductor 53 to the switch D which is closed during flight, and from said point by way of conductor 54 to the solenoid 10' the return circuit being by way of conductor 14'. A similar failure in the three-engine arrangement of Fig. 4 would likewise result in energization of the solenoid 10', the circuit being from the source 13' by way of conductors 61, 62 and 63 to the solenoid 10' and returning by way of conductors 64, 65, switch F (closed during flight), conductors 66 and 67 and the now closed switch A (although normally open during flight—that is, with the engine running) and back to the source 13' by way of conductors 68 and 69.

What we claim is:

1. The combination with an internal combustion engine and propeller shaft rotated by said engine, of means for arresting the rotation of said propeller shaft, and temperature controlled electromagnetic means for controlling said arresting means.
2. The combination with an internal combustion engine and propeller shaft rotated by said engine, of means for arresting the rotation of said propeller shaft, and electromagnetic means for controlling said arresting means, a circuit including a source of current to energize said electromagnetic means, and means normally holding said circuit open said last named means including a switch in said circuit, and means responsive to the heat developed upon operation of the engine to move said switch to the open circuit position.
3. The combination with an internal combus-

tion engine and propeller shaft rotated by said engine, of means for arresting the rotation of said propeller shaft, and electromagnetic means for controlling said arresting means, a circuit including a source of current to energize said electromagnetic means, and means normally holding said circuit open said last named means including a switch in said circuit, and means responsive to the heat developed upon operation of the engine to move said switch to the open circuit position said heat responsive means being also adapted to return the switch to the closed position when the engine cools to a predetermined extent after stopping.

4. The combination with a plurality of internal combustion engines, of a corresponding plurality of brakes engageable with the respective propeller drives, electromagnetic control means for said brakes, and means including a common source of energy for operation of said electromagnetic control means said last named means also including a circuit having a series of switches therein, and means individual to each engine to control operation of a selected one of said switches.

5. The combination with a plurality of internal combustion engines, of a corresponding plurality of brakes operable upon the respective engines, actuating means for said brakes, and means individual to each engine to control application of the brake to a selected engine, and the release of the brake from all engines whenever the brake being applied is not the first in the series.

MARTIN J. FINNEGAN.
HOWARD BAER.
